UNITED STATES PATENT OFFICE.

OBERLIN SMITH, OF BRIDGETON, NEW JERSEY; PERCIVAL H. SMITH EXECUTOR OF
SAID OBERLIN SMITH, DECEASED.

PHONOGRAPH.

Application filed June 25, 1926. Serial No. 118,582.

This invention concerns automatic phonographs such as that of the patent of Oberlin Smith No. 1,573,504, dated February 16, 1926, and the application of Oberlin Smith No. 712,317, filed May 10, 1924, wherein a number of records are placed in a magazine or holder from which one at a time they are automatically taken and placed upon the turntable of the phonograph and after being played are returned to their proper position in the holder or magazine. The object of this invention is to enable disc records of different diameters to be placed in the same magazine.

This invention consists in whatever is described by or is included within the terms or scope of the appended claims.

In the annexed drawings:

Fig. 1 is a vertical section showing enough of an automatic phonograph to illustrate one embodiment of my invention;

Fig. 2 is a similar view of another embodiment of my invention;

Fig. 3 is a side elevation thereof.

It will be unnecessary to describe in any detail the mechanism by which records are moved from the magazine or holder to the turntable and returned to their place in the magazine. It is enough for the purpose of this application to state that such mechanism may be that of the patent and application above mentioned or any other suitable for the purpose. The present invention is not concerned with that mechanism or part of the machine, but with the means by which disc records of different diameters may be used in the same machine. The present invention takes advantage of or makes use of the fact that the records of different sizes, say ten inch records and twelve inch records, differ in weight. The magazine or holder, 10, shown in the drawings is of the type shown in the patent and application above mentioned, which comprises a horizontally traveling support with side by side racks, one for each record formed by slots or spaced partitions, in which the disc records are supported at their bottom edges in a vertical position, so that by the lifter mechanism, a record may be lifted from its place in the magazine.

Provision is made of two supports in each record holding slot or space. One of these supports is a fixed or stationary one consisting, as shown in the drawing, of two op-

positely spaced ledges, 12, situated to engage the edge of the disc at the bottom on opposite sides of a vertical line passing through the center of the disc, this stationary support being for the records of largest diameter. The other support is a movable one, consisting as shown in the drawing, of a lever, 13, that is pivoted on a horizontal pivot, 14, at a point below the bottom edge of the largest record, when in the rack, such lever having a record-disc engaging portion that is situated between the two ledges which constitute the stationary support, so that the lever may swing up and down, the lever being moved downward and out of the way when the record of largest diameter engages it, the weight of the lever not being sufficient to overcome the weight of the largest disc, but the lever being by a suitable counter-balance, able to exert a lifting pressure upon the record of smaller diameter to support the record of smaller diameter, so that its central hole will align with the central hole of the larger records when in the magazine. Thus, all of the records whether large or small have their central holes (which engage the central pintle of the turntable of the phonograph) at the same point or in the same plane in the magazine or holder. As shown in the drawings, the lever, 13, has a counterbalance, 15, which will cause the lever to lift and support the small record with its center in the position as above mentioned.

In the embodiment of my invention illustrated in Figs. 2 and 3, is shown a record transferring mechanism similar to that of my application No. 712,317, filed May 10, 1924, and the weighing or compensating means are provided in the lifter and not in the magazine or holder. In this case, the holder, 100, has near the bottom opposite stationary record-supports, which may be two parallel rods, 120, which by reason of the difference in diameter of the records will support the records with their centers at varying heights to a fixed extent. Carried by the head or frame-work, 16, of the lifter mechanism to which the gripper jaws, 17, are pivoted, are two vertically movable pins, 18, each of which is yieldingly supported by a coil spring, 19, these springs being accurately matched compression coil springs, and capable of yielding downward under the weight of the larger record when the upper ends or heads, 20, of the pins

- contact with the larger record, but which will not yield under the weight of the smaller record, and therefore, when they engage the smaller record, the latter will be carried up by the lifter and in due course the grippers will close upon the smaller record and grip it for transportation to the turntable of the phonograph. To engage the lower edge of a larger record and lift the same when the yieldable smaller record engaging pins are depressed under the weight of the larger record, there are two oppositely located pins, 21, carried by one of the gripper jaws which engage the record before the jaws close upon it. Preferably the heads, 20, of the yieldable record engaging pins are T-shape, as best shown in Fig. 3, and one arm of the T is utilized to engage an inclined or cam projection, 22, on the top of the box or casing, 23, of the phonograph, when the grippers swing down with the record to place it upon the turntable, so as to press the rods sufficiently far from the edge of the record lying on the table to prevent contact with the edge of said record, which might otherwise occur. What is the under gripper at the time of this operation has a hole, 24, for the passage of the cam. Of course, the yieldingly supported rods are prevented from turning.
- It will be seen that by this invention in the most simple and yet efficient way, record discs of different sizes may be used in the same automatic machine.
35. What is claimed is:
- 1. A magazine or holder for records of automatic playing machines having means to support in the same record receiving space records of different diameters at different times and means movable in the plane of a record towards and from such space and having a record edge-engaging surface to move the record out of such space.
  - 2. A magazine or holder for records of automatic playing machines having means to support in the same record receiving space records of different diameters at different times, and means for moving a record when in such space, comprising a movable element 50 that directly engages the record.
  - 3. A magazine or holder for records of automatic playing machines having means to support in the same record receiving space records of different diameters at different times, comprising a movable record engaging device that yields under the weight of one record, but does not yield under the weight of another record.
4. A magazine or holder for records of automatic playing machines having means to support in the same record receiving space records of different diameters at different times, comprising a stationary record support and a movable record support that yields under the weight of a record of a size 65 to engage the stationary support.
5. An automatic playing machine using disc records having a holder for records of different sizes all of which are to be placed on the same turntable, means for moving anyone of such records from the holder to the turntable, and automatic means for compensating for difference in record sizes 70 whereby all records will be delivered properly to the turntable.
6. An automatic playing machine using disc records having a holder for records of different sizes all of which are to be placed on the same turntable, and means for compensating for difference in record sizes 75 whereby all records will be delivered properly to the turntable, said means comprising a yieldable record engaging device adapted to yield under the weight of larger records.
7. An automatic playing machine using disc records having a holder for records of different sizes all of which are to be placed on the same turntable, and transferring means having sets of record-engaging means, one set being yieldable under the weight of 80 the larger records.
8. An automatic playing machine using disc records having a holder for records of different sizes all of which are to be placed on the same turntable and record-engaging means comprising a stationary element for records of one size and a yieldable element for records of the other size adapted to yield under the weight of the larger records.

In testimony whereof I hereunto affix my 100
signature.

OBELIN SMITH.
